[57] CLAIM

The ornamental design for the aircraft shelter or similar structure, as shown and described.

DESCRIPTION

FIG. 1 is a perspective view of an aircraft shelter or similar structure showing my new design;

FIG. 2 is a top plan view thereof;

FIG. 3 is a front elevational view thereof;

FIG. 4 is a rear elevational view thereof;

FIG. 5 is a side elevational view thereof;

The aircraft shown in dotted lines in FIGS. 2-5 is disclosed for illustrative purposes only and forms no part of the claimed article.

FIG 1

FIG 2

FIG 3
